CLAIM

The ornamental design for a heat dissipating and surge protection housing for stereo equipment, as shown and described.

DESCRIPTION

FIG. 1 is a top, front, right side perspective view of a heat dissipating and surge protection housing for stereo equipment showing my new design;

FIG. 2 is a front elevational view thereof;

FIG. 3 is a rear elevational view at a reduced scale thereof;

FIG. 4 is a right side elevational view of FIG. 1;

FIG. 5 is a left side elevational view of FIG. 3;

FIG. 6 is top plan view of FIG. 1; and,

FIG. 7 is a bottom plan view of FIG. 1.

FIG. 1

FIG. 2

FIG. 4

FIG. 3

FIG. 5

FIG. 7

FIG. 6
